UNITED STATES PATENT OFFICE.

MAX MAYER, OF FORT LEE, AND THOMAS YEO, OF UNION HILL, NEW JERSEY,
ASSIGNORS TO M. J. WOHL & CO., OF BROOKLYN, NEW YORK, A CORPORA-
TION OF NEW YORK.

DIFFUSING-SCREEN.

1,361,344.

Specification of Letters Patent.

Patented Dec. 7, 1920.

Application filed October 30, 1919. Serial No. 334,596.

To all whom it may concern:

Be it known that we, MAX MAYER, a citizen of the United States, and resident of the town of Fort Lee, in the county of Bergen 5 and State of New Jersey, and THOMAS YEO, a citizen of the Dominion of Canada, and a resident of the town of Union Hill, in the county of Bergen and State of New Jersey, have invented certain new and useful Im- 10 provements in Diffusing-Screens, of which the following is a specification.

This invention relates to improvements in screens adapted for use as light diffusing devices in connection with sources of artificial 15 light for photographic purposes and particularly to that class of such devices, in which a sheet of pliable material, as spun glass or the like, is used as diffusing medium.

It is the object of the present invention, to provide an improved device of this character, comprising a frame for holding the diffusing material securely and permitting its removal and facilitating its renewal 25 without injury to either the frame, or the diffusing material.

With these and other objects in view the invention consists in certain novel details of construction and arrangement of parts, 30 hereinafter described and shown and illustrated in the accompanying drawings, made part of this specification, in which:

Figure I is a front elevation, showing the upper half of a diffusing screen embodying 35 the invention.

Fig. II is a vertical section through Fig. I on the line A—A.

Fig. III is an enlarged front elevation showing in detail a corner of the diffusing 40 screen shown in Figs. I and II.

Fig. IV. is a sectional side elevation of Fig. III.

Fig. V. is a front elevation of the lower half of a diffusing screen provided with a 45 modification of the clamping means.

Fig. VI. is a vertical section through Fig. V taken on the line B—B.

Fig. VII. is an enlarged front elevation, showing in detail a corner of a diffusing 50 screen as shown in Figs. V and VI.

Fig. VIII. is a sectional side elevation of Fig. VII.

Similar characters of reference indicate 55 corresponding parts throughout the various views.

The diffusing screen consists of a sheet 1 made of fine spun strands 1^a of non-combustible and translucent material, preferably glass, disposed parallel to each other, forming the warp of the sheet. These strands are 60 supported and retained in position by spaced metallic cross wires 2 which are woven into the sheet, forming its woof, and serve to stiffen it. A rectangular sheet of diffusing material so constructed, is preferably held 65 in a frame of suitable size formed by shaped moldings of metal, either pressed from a solid sheet, or mitered at the corners and joined by welding or any other suitable process. As shown in Figs. I to IV, the diffuser 70 frame consists of a base molding 3 consisting of a flat portion and a ledge formed thereon by two bends 3^a and 3^b along the opening of the frame. The cover section 4 of the frame is formed to fit the base section 75 having a similar ledge consisting of bends 4^a and 4^b. The diffusing sheet 1 is held between base section 3 and cover 4 being pressed to assume a bent shape between their ledges 3^a—3^b and 4^a—4^b. The base and cover 80 sections are clamped against each other to firmly hold sheet 1 by means of the U-shaped channels 5 which are preferably resilient and held in place near the corners of the frame by pins or clinch rivets 6 extending 85 through apertures in sections 3, 4, and channels 5.

In Figs. V to VIII a modification of the holding frame is shown. In this construction the base section 7 of the frame is also 90 provided with ledges 7^a and 7^b surrounding the opening of the frame, but the outward edges of this section are formed by a reverse bend into a U shape at 7^c and 7^d. The cover section 8 of this frame corresponds in shape 95 to that of cover section 4, but its outer dimensions are such that the cover section can be inserted into base section 7, its outer edges passing the inwardly turned edges of 7^a. At various places of the cover 8 oscillating latch 100 bars 9 preferably made from resilient material are fastened by means of pins 10 which when opened are in a position as shown at 9^a Fig. V and when closed rest with their outer faces against the inner face of 105 ledge 7^d and thereby press section 8 against the diffusing sheet, lying between this section and base section 7.

The operation of inserting and removing a sheet of diffusing material is easily accom- 110

plished in either construction by opening the clamping means, removing the pins 6 and channels 5 from the frame shown in Figs. I to IV or turning the latch bars 9 into the 5 position shown at 9^a when using a frame as illustrated in Figs. V to VIII. The cover and base sections may then be separated, a diffusing sheet placed flat upon the base section and pressed to take a bent shape along 10 its edges by pressing the cover section against the base section, which effects a stretching of the body part of the sheet by tying it over the bends 3^a (or 7^a), and replacing the clamping means.

15 As the diffusing medium must be very tightly fastened to the frame along its edges, it was customary heretofore to permanently fasten the diffusing sheet into a 20 frame and abandon the frame with a worn diffusing sheet.

By the present invention this difficulty is overcome by means of the bend producing an indentation in the diffusing sheet along the inner edges of the frame which 25 prevent a slipping of the sheet in the frame and which tend to stretch the sheet while it is being inserted into the frame. The invention also makes it possible to use diffusing sheets of different colors in the same 30 frame.

Having thus described our invention, what we claim as new and desire to secure by Letters Patent is:

1. In a device of the kind described, a 35 frame including means to stretch and clamp a sheet of pliable material, formed by bars permanently joined at their ends, said frames being separable along a plane parallel to said sheet and clamping means concealed within the outlines of said bars to give an unobstructed polygonal outline to said frame.

2. In a device of the kind described, a 45 frame including means to stretch and clamp a sheet of pliable material, separable along a plane parallel to said sheet, said frame and said clamping means consisting of shaped flat metallic bars, said clamping means forming the front and rear sides of 50 said device into extended parallel planes.

3. In a device of the kind described a sheet of pliable material, a frame formed by bars permanently joined at their ends leaning against one side of said sheet, pressing means leaning against its opposite side and resilient clamping bars forming alining guides at the outer faces of said frame adapted to clamp said sheet between said 55 pressing means and said frame.

60 4. In a device of the kind described a sheet of pliable material, a frame formed by bars permanently joined at their ends leaning against one side of said sheet, pressing means leaning against its opposite side

and clamping bars lying flat against said 65 pressing means and said frame on opposite sides to form parallel guides at the outer edges of said device to clamp said sheet between said pressing means and said frame.

5. In a device of the kind described a 70 sheet of pliable material, a pair of frames leaning against opposite faces of said sheet, means on said frames coöperating with each other, to deflect under pressure a margin completely surrounding said sheet and resilient 75 clamping bars lying flat against opposite faces of said frames removably fastened thereto.

6. In a device of the kind described a 80 sheet of pliable material, a frame supporting the border of said sheet on opposite faces and including means to produce a deformation of said border completely surrounding said sheet and separable clamping means adapted to hold said sheet within 85 said frame in deformed position and forming a rectangular outline on said device.

7. In a device of the kind described, a 90 sheet of pliable material, a frame consisting of shaped metal moldings permanently joined at their ends supporting the border of said sheet on opposite faces and including means to produce a deformation of said border under pressure and clamping latches concealed within the front and rear faces 95 of said moldings, adapted to hold said sheet rigidly within said frame in deformed position.

8. In a device of the kind described a 100 sheet of pliable material a frame surrounding the edges of said sheet and leaning against one of its faces, pressing means leaning against the opposite face of said sheet and clamping means movably fastened to said pressing means, adapted to coöperate with means on said frame to hold said pressing means in place on said frame.

9. In a device of the kind described, a 110 sheet of pliable material, a frame consisting of a single sheet-metal molding leaning against one face of said sheet along its border, a ledge along the face-opening of said frame, and pressing means consisting of a similarly formed sheet-metal molding adapted to stretch said sheet and clamping 115 means within the outlines of said moldings to hold said sheet within said frame.

10. A diffusing screen consisting of a 120 sheet of pliable material, interposed between a pair of matched sheet-metal moldings forming a frame, and having an offset in transverse section adapted to deform said sheet under pressure and clamping means to press said moldings against said sheet inclosed within the outlines of said frame. 125
